UNITED STATES PATENT OFFICE.

DAVID GOLDSTEIN, OF SAN FRANCISCO, CALIFORNIA, ASSIGNOR TO HENRY GOLDSTEIN, OF SAME PLACE.

SAMPLE-TRAY.

SPECIFICATION forming part of Letters Patent No. 376,739, dated January 24, 1888.

Application filed March 29, 1887. Serial No. 232,910. (No model.)

To all whom it may concern:

Be it known that I, DAVID GOLDSTEIN, a citizen of the United States, residing at San Francisco, in the county of San Francisco and 5 State of California, have invented a new and useful Sample-Tray for Holding and Displaying Wares in Show-Cases, of which the following is a specification.

My invention relates especially to trays for 10 displaying articles of hardware, cutlery, and similar small goods and merchandise in show-cases.

The invention consists in the construction 15 and combination of parts hereinafter described, and pointed out in the claims.

In the accompanying drawings, forming a part of this specification, Figure 1 is an elevation in cross section through a set of trays and show-case. Fig. 2 is a perspective view of 20 one support and portions of the tray at one end. Fig. 3 is a plan or top view of a tray. Fig. 4 is a view of the tray and the detachable bottom, these parts being separate. Fig. 5 is a perspective view of the end portion of a 25 tray with the end removed.

A A represent the trays, and B an inclosing-case, having glass top and front, after the usual form.

C is a stringer or support setting upright 30 at each end of the case, and having rests or guides d at suitable distance apart rising one above another, and also extending from the rear end forward to the front of each step or riser C. Two of these supports being set and 35 fixed in position, the trays are slipped into place from the rear, one above another; and, sliding on the guide-strips d, they are pressed forward, each one to the end of its supports. A position in the form of steps is thus given 40 to the trays, and the entire top surface of each tray is exposed to view through the front and top of the case. Each tray is, moreover, independent of the others in its movement, and can be readily withdrawn at any time from 45 the case to show the samples to customers without necessitating the handling of the other trays.

The top surface, a, of the tray is made to hold samples of the different grades, qualities, 50 or kinds of the articles contained in the case: and to confine or fasten them in place I use

elastic tapes or straps of the usual manner of securing various articles or sample-cords, but as an improvement upon such mode of attaching samples.

I combine and provide at each strap or tape E a lifting-ring, E^x, for the purpose of enabling the tape to be drawn up clear of the board and the sample to be withdrawn without touching the fingers to the polished or metal surface of 60 the sample, and for the further purpose of rendering it easier to seize the tape to raise it.

The holding-tapes and their lifting-rings are shown in Figs. 4 and 5. The tapes are stretched across the top surface of the tray in one, two, 65 or more lines, as required by the size and form of the articles, and they are fixed at intervals to the surface by tacks f, leaving the portions between these points loose and free to be lifted from the surface for inserting the 70 sample under the tape. To each of the unattached portions between the points f is provided the lifting-ring E^x. G is a box-like bottom to be fastened against the under side of the tray, and having sides and ends of suitable 75 height to leave a space between the bottom and the tray for a receptacle to contain duplicates of the articles that are fastened upon the exhibiting-surface of the tray. This part A is secured to the bottom by hooks g or other 80 suitable catches in such manner that the two are fastened together and readily moved in and out in withdrawing or replacing a tray. In receptacles thus provided the articles, of which samples are exhibited on the top A, 85 can be placed and stored away, and, if found desirable, the space may be divided into compartments by cross-partitions corresponding to the divisions upon the top, whereby each sample-space on the tray will have a compartment appropriated to it in the box beneath, and from which an article can be easily taken 90 to supply the customer without handling or disturbing the sample.

As the sample-holding part A is made detachable from the bottom G, it can be readily lifted off to give access to the article in the compartment or to show the samples to a customer without requiring the salesman to handle or carry this heavier bottom part, particularly when it is filled with goods.

Now, as thus constructed and arranged for

operation and use, it will be seen that there is considerable economy in space within the show-case. The articles are presented to view in such complete, attractive, and convenient manner that not only is there considerable saving in time to the customer as well as the salesman, but the articles are kept from being tarnished or injured by handling. It also affords convenience in the marking of goods, as to the back edge of the tray furnishes a surface to hold price-marks for the sample occupying a position on the tray in line with the mark, while to the bottom or under side of the tray can be affixed price-lists or descriptions of quality and other matter of importance to the salesman.

Having thus described my invention, what I claim, and desire to secure by Letters Patent, is—

- 20 1. The herein-described exhibiting device, consisting of a case, a series of supports therein arranged in steps, the projecting portion of each being about the dimensions of a tray,

and trays or holders inserted through the rear of the case and held on the forward end of said supports, so that the whole top of the tray shall be displayed, and elastic sample-holding clamps on the tops of said trays, and compartments in the body thereof, as set forth.

2. The herein-described exhibiting device, 30 consisting of a case having a series of supports therein arranged in steps, the projecting portion of each being about the dimensions of a tray, and trays or holders inserted through the rear of the case and held in the projecting 35 portions of the supports, said trays having elastic tapes E, secured on their tops, and rings E^x, secured in and extending above the tapes, as set forth.

In testimony that I claim the foregoing I 40 have hereunto set my hand and seal.

DAVID GOLDSTEIN. [L. S.]
